(57) **CLAIM**

The ornamental design for a guide for battery, as shown and described.

DESCRIPTION

FIG. 1 is a front perspective view showing the overall configuration of a guide for battery according to our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a bottom perspective view thereof; and,

FIG. 9 is an enlarged view showing a portion 9 of FIG. 1. The broken lines of uneven length in FIGS. 1 and 9 that encircle a portion of the guide for battery form no part of the claimed design.
